UNITED STATES PATENT OFFICE.

CHARLES HOLMES CALER, OF NEW BRIGHTON, PENNSYLVANIA.

WINDOW-LOCK.

No. 912,805.

Specification of Letters Patent.

Patented Feb. 16, 1909.

Application filed July 13, 1908. Serial No. 443,187.

To all whom it may concern:

Be it known that I, CHARLES HOLMES CALER, a citizen of the United States of America, residing at New Brighton, in the county 5 of Beaver and State of Pennsylvania, have invented certain new and useful Improvements in Window-Locks, of which the following is a specification, reference being had therein to the accompanying drawing.

10 This invention relates to window-locks, and the primary object of my invention is to provide a window-lock applicable to window-sashes of various sizes, the lock being easily and quickly manipulated to retain the sashes 15 of a window in a closed position or in a position to which they may be adjusted.

A further object of this invention is to provide a simple, inexpensive and durable lock comprising two hinged members adapted to 20 be swung into position to lock the sashes of a window, firmly hold the same, and prevent the window from being surreptitiously opened.

With the above and other objects in view which will more readily appear as the invention 25 is better understood, the same consists in the novel construction, combination and arrangement of parts to be presently described and then specifically claimed.

In the drawings:—Figure 1 is a perspective 30 view of my window-lock as applied to window-sashes, Fig. 2 is a horizontal sectional view of the same, illustrating the lock in plan, and Fig. 3 is a perspective view of the hinged members of the lock.

35 In the accompanying drawings, 1 designates a window-frame having stop beads 2 for the stiles 3 of window-sashes adjustably mounted between said beads. The stiles 3 of the upper sash are cut away or recessed, as at 40 4, for the reception of bearing plates 5 having apertured lugs 6 for a connecting pintle 7. Lock members 8 are hinged to the bearing plates 7 by the pintle 7, and when these members are swung into engagement with the 45 plates 5, the outer faces of said members lie flush with the surface of the stile 3.

Mounted upon the meeting rail 9 of the lower sash is a beveled plate 10 having a lip

11. The lower hinged member 8 is adapted to be swung outwardly to engage the plate 10 50 and hold the meeting rails of the sashes together, whereby one sash cannot be elevated or lowered with respect to the other sash. By swinging the lower hinged member inwardly, the sashes can be adjusted whereby 55 the upper hinged member will engage the plate 10, thus retaining the sashes in a partially open position.

I reserve the right to use a plurality of hinged members that can extend from the 60 meeting rail of the upper sash to the top rail thereof, thereby permitting the sashes to be located in any adjusted position.

I construct my lock of light and durable metal, and while in the drawings forming a 65 part of this application there is illustrated the preferred embodiments of the invention, I would have it understood that the elements therein can be varied or changed without departing from the spirit of the invention. 70

Having now described my invention what I claim as new, is:—

In a window-lock, the combination with a sash stile having recesses in one face thereof, of plates countersunk in said recesses and 75 provided with apertured lugs, locking members hinged to said plates, a pintle materially longer in length than the combined length of the plates and constituting a pivot for said locking member and connecting one 80 plate with the other plate, one of said plates connected to one end of said pintle and the other plate to the other end of the pintle, the said locking members when against the plates lying within the recesses in the stile with their 85 outer faces flush with the outer face of the stile, said locking members each movable independently of the other, and an inclined stop plate secured to the sash meeting rail to engage said locking members. 90

In testimony whereof I affix my signature in the presence of two witnesses.

CHARLES HOLMES CALER.

Witnesses:

AUGUSTUS A. JAMISON,
L. O. BARNES.
